The ornamental design for a unit for extending the function of electronic computers, as shown and described.

[52] **U.S. Cl.** ..... **D14/107****CLAIM**[58] **Field of Search** ..... D14/100, 107, D14/114; D13/184, 199; 361/683-686; 364/708.1[56] **References Cited****DESCRIPTION****U.S. PATENT DOCUMENTS**

FIG. 1 is a top, front and right side perspective view of a unit for extending the function of electronic computers showing my new design;

- D. 311,387 10/1990 Brenneman et al. D14/100
 D. 320,196 9/1991 Carter et al. D14/107
 D. 331,920 12/1992 Iino D14/107
 D. 332,091 12/1992 Iino D14/107
 D. 335,490 5/1993 Mesfin et al. D14/107
 D. 336,287 6/1993 Mitzusugi et al. D14/107
 D. 342,060 12/1993 Iino D14/107
 D. 342,487 12/1993 Iino D14/107
 D. 359,034 6/1995 Kondo D14/107
 4,084,213 4/1978 Kirchner et al. 361/680
 5,126,954 6/1992 Morita 361/683
 5,182,699 1/1993 Kobayashi et al. 361/683
 5,283,714 2/1994 Tsai et al. 361/683

FIG. 2 is a front elevational view thereof;

FIG. 3 is a top plan view thereof;

FIG. 4 is a rear elevational view thereof;

FIG. 5 is a right side elevational view thereof, the left side being a mirror image;

FIG. 6 is a bottom plan view thereof;

FIG. 7 is a top, front and right side perspective view thereof with the apparatus being in a closed position; and,

FIG. 8 is a top, front and right side perspective view thereof showing the use of the apparatus.

The pattern is partially shown in the figures for ease of illustration and it is understood to continue uniformly across each of the indicated surfaces and the broken lines are shown in FIG. 8 for illustrative purposes only and form no part of the claimed design.
